CHINA CABINET

Ernest Herrmann, Westport, Conn., assignor to Heywood-Wakefield Company, Gardner, Mass., a corporation of Massachusetts

Application August 8, 1958, Serial No. 52,126

Term of patent 7 years

(Cl. D33—19)

Fig. 1 is a front view of a china cabinet, showing my new design;

Fig. 2 is a sectional view on the line 2—2 of Fig. 1, but on a larger scale; and

Fig. 3 is a fragmentary sectional view on the line 3—3 of Fig. 1, but on a larger scale.

The back and sides of the china cabinet are plain and of conventional configuration.

The dominant features of the design are the parts shown in full lines.

I claim:

The ornamental design for a china cabinet, substantially as shown and described.
